BENJAMIN F. MILLER, OF NEW YORK, N. Y.

Letters Patent No. 71,630, dated December 3, 1867.

VENTILATING-COWLS.

The Schedule referred to in these Letters Patent and making part of the same.

TO ALL WHOM IT MAY CONCERN:

Be it known that I, BENJAMIN F. MILLER, of the city and State of New York, have invented and made a certain new and useful Improvement in Ventilators; and I do hereby declare the following to be a full, clear, and exact description of the said invention, reference being had to the annexed drawing, making part of this specification, wherein—

Figure 1 is a section of my ventilator complete.

Figure 2 is a vertical section of a ventilator with the front water-escape left out, and

Figure 3 is an elevation of the front of my ventilator, with perforated doors applied thereto.

Similar marks of reference denote the same parts.

Heretofore injecting-ventilators, for supplying fresh air to vessels and buildings, have been made with a wind-sail, from which a canvas pipe extends to the apartment to be ventilated. Other ventilators for the same object have been made of sheet metal, with a funnel-shaped mouth to receive the air. On account of these being kept with the mouth to the wind, the rain and spray often beat in and greatly inconvenience the occupants of the apartments ventilated; and the currents of air being concentrated by the funnel mouth, form eddies that prevent the rapid movement of the air.

The nature of my said invention consists in a ventilator for injecting air, formed with nearly parallel sides, and a mouth contracting in two directions, and opening into a curved passage leading to the space to be supplied with fresh air. By this means the eddies and counter-currents are avoided. I also provide water-dams, in such position that rain or spray will not pass down the ventilator.

In the drawing, *a* represents the base of the ventilator, which may be circular, so as to be turned by the action of the wind or otherwise, into the position required for the ventilator to receive the wind. *b* is a square trunk rising from the base *a*, and curving into the nearly semicircular trunk *c*, that is formed between the sides *d d* and the curved plate *e*, forming the back and top of the ventilator. Between the sides *d d* the inclined shedding-plate *f* is introduced, to form the bottom of the mouth that by these plates, *e* and *f*, is contracted in two directions, and opens into the curved trunk *c*. Any water that falls upon the plate *f* will run out again, unless the force of the wind drive it up the same. To provide against this contingency, I introduce the plate *g*, that leaves an opening at 2, for water to pass off the upper end of the plate *f*, and run down above the plate *g*, and out at holes 3. Spray or rain dashing into the ventilator, and falling upon the side plates *d d* is prevented from running down those plates and into the apartment ventilated, by the flange-plates 5, secured to the interior faces of plates *d*, and running from the upper edge of the plate *f* down to the ends of the opening 4, to direct such moisture out through such opening. These flanges 5 only require to be small, narrow strips, and do not obstruct the air. In case of snow, or when too much air passes down the ventilator, the perforated doors *h h* may be closed. These doors are formed of sheet metal, hinged at their outer edges to the plates *d d*, and when open they may project forward of the edges of these plates *d d*, and flare outwards, so as to direct the current of air in entering the ventilator. The curved air-passage *e* enables me to introduce the plate *f*, so as to cover the trunk *b*, for preventing water passing through the ventilator, and at the same time the air is not obstructed in its passage. The plates *e* and *f* may extend sufficiently forward to balance the weight, that the whole ventilator may turn freely on a vertical pivot.

What I claim, and desire to secure by Letters Patent, is—

1. The curved air-passage *e*, extending from the trunk *b* to the mouth of the ventilator, as and for the purposes set forth.
2. The inclined plate *f* and plate *g*, in combination with the openings 2 and 3, for receiving and discharging water that may enter the ventilator, as set forth.
3. The opening 4, at the lower end of the curved plate *e*, for the purposes and as set forth.
4. The flange-plates 5, upon the plates *d*, extending from the plate *f*, to direct moisture out through the opening 4, as specified.
5. The perforated doors *h h*, in combination with ventilator, formed with the curved air-passage *e* and flaring mouth, as and for the purposes set forth.

Dated July 13, A. D. 1867.

B. F. MILLER.
